UNITED STATES PATENT OFFICE.

ROBERT HELMER, OF HECTOR, MINNESOTA.

DANCING TOY.

No. 817,772.

Specification of Letters Patent.

Patented April 17, 1906.

Application filed September 21, 1905. Serial No. 279,519.

To all whom it may concern:

Be it known that I, ROBERT HELMER, a citizen of the United States, residing at Hector, in the county of Renville and State of Minnesota, have invented certain new and useful Improvements in Dancing Toys, of which the following is a specification.

This invention has relation to amusement devices, such as movable toys, which simulate the movements of dancers and acrobats, the purpose being to provide, in combination with the figure, means for beating time, thereby adding greatly to the interest of the toys' performance.

15 The invention consists of a jointed figure, a support therefor, such as a spring, which will not interfere in the least with its free movements, a platform of textile or like flexible sheet material, and a vibrating mechanism 20 for jarring the platform to cause the figure to dance and assume grotesque positions.

25 For a full description of the invention and the merits thereof and also to acquire a knowledge of the details of construction of the means 20 for effecting the result reference is to be had to the following description and accompanying drawings.

While the invention may be adapted to different forms and conditions by changes in the 30 structure and minor details without departing from the spirit or essential features thereof, still the preferred embodiment is shown in the accompanying drawings, in which—

35 Figure 1 is a perspective view of a dancing toy embodying invention. Fig. 2 is a view of the same as seen from the under side. Fig. 3 is a transverse section of the toy on the line $x-x$ of Fig. 2 looking in the directions of the arrow. Fig. 4 is a detail view of a portion of 40 the toy and its spring-support.

Corresponding and like parts are referred to in the following description and indicated in all the views of the drawings by the same reference characters.

45 The figure 1 is provided with jointed limbs and may be of any design, according to the character of the toy. The support 2 consists, preferably, of a spring-wire sufficiently stout to sustain the figure without interfering in 50 the least with its free movements and which will supplement the action of the vibrating or jarring mechanism by means of which the toy is set in motion. The spring-wire 2 is curved, and its upper portion is bent downward, as shown at 3, thence horizontally, as

indicated at 4, to provide an arm upon which the figure is loosely mounted so as to freely oscillate. In the event of the figure being of flattened form, as when constructed of sheet material, it is provided with a horizontal tube 60 5, through which the arm 4 passes, the projecting end of the arm being bent to retain the figure in place, the bent portion 3 constituting an inner stop to limit the movement of the figure toward the support. The figure is 65 nicely balanced upon the supporting-arm 4, so as to maintain a given position and yet admit of its free oscillation so as to add materially to the grotesqueness of its actions. The platform 6 is preferably of textile or like 70 flexible sheet material and is stretched over a framework, which in the present instance consists of a box or hollow base 7, having an opening in its top directly below the toy and over which the textile material forming the plat- 75 form is stretched.

In the operation of the toy the platform is jarred or vibrated, thereby causing the figure to move up and down in rapid succession, the articulation of its limbs and the loose mounting thereof upon the support adding to the 80 variety of movement and grotesqueness of action.

The vibrating or agitating mechanism is arranged within the box and beneath the platform and consists of a flat spring 8 and tappet-wheel 9, the spring 8 being secured at one end to the framework and provided at its opposite end with a knocker 10, arranged to come in contact with the platform and impart a vibratory movement thereto. The tappet-wheel 9 is fast to a shaft 11, journaled lengthwise of the framework and provided at its outer end with a crank 12 to be operated by hand. The tappet-wheel 9 is provided 95 around its periphery with spurs which successively engage with the spring 8 in the rotation of the shaft 11 and cause said spring to vibrate and the knocker 10 carried thereby to impart a corresponding movement to the 100 platform, whereby the toy has movement imparted thereto.

Having thus described the invention, what is claimed as new is—

A dancing toy consisting of a box-like 105 framework having an opening in its top, a textile stretched over said opening and forming a platform, a jointed figure having a horizontal tube, a spring-support attached at one end to the framework and having its oppo- 110

site end bent and passed loosely through said tube and provided with a stop at each end of the tube, a vibrating mechanism located within the framework and comprising a flat 5 spring secured at one end to the framework and having a knocker at the opposite end to come in contact with the aforesaid textile platform, a tappet-wheel for coöperation with the spring, and a shaft having said tappet-

wheel fast thereon and provided at its outer 10 end with an operating-crank.

In testimony whereof I affix my signature in presence of two witnesses.

ROBERT HELMER. [L. S.]
